UNITED STATES PATENT OFFICE

2,200,800

PLATE LIFTER

Edgar R. Miller, Chicago, Ill., assignor to F. J. Littell Machine Co., Chicago, Ill., a corporation of Illinois

Application September 28, 1939, Serial No. 296,876

4 Claims. (Cl. 294—64)

This invention relates to a new and improved plate lifter or the like, and more particularly to a device of this character operating by means of suction created by a fluid under pressure.

A plate lifter of this type is of particular utility in handling plates, sheets or shapes formed of metal or other material which is substantially impervious to air and may consequently be lifted and moved by a suction grip. A suction lifter of this type is useful in handling sheets or plates which because of their shape or size may be difficult to move by hand or with mechanical means, such as tongs. This device is also important in its safety advantages in that sheets may be introduced within or removed from a punch or shaping press without inserting the hand or fingers within the zone of the moving parts. The suction cups may be located at the end of relatively long supporting arms so that the work may be handled well within the machine without endangering the operator.

It is an object of the present invention to provide a new and improved plate lifter or the like, of the suction type.

It is a further object to provide a device of this character which gives a substantial suction derived from the flow of fluid, such as compressed air, under comparatively low pressure.

It is an additional object to provide a plate lifter utilizing the discharge of fluid under pressure through a Venturi-like orifice to create the desired suction.

It is also an object to provide a construction in which the relationship of the discharge, Venturi and suction orifices may be readily adjusted.

It is a further object to provide a plate lifter composed of but few and simple parts and adapted for commercial production and use.

Other and further objects will appear as the description proceeds.

I have shown a preferred embodiment of my invention in the accompanying drawing, in which—

Figure 1 is an elevation of the lifting device;

Figure 2 is a section on an enlarged scale through the suction head body; and

Figure 3 is a plan view of the suction end of the device showing a modified form of construction.

In the drawing, the pistol grip 11 is provided with the hose connection 12 for receiving compressed air. This grip is provided with a valve controlled passage connecting the hose or similar conductor 12 and the discharge pipe 13. The valve stem 14 is compressed by means of trig-

ger 15 to open the valve. The valve may be of any usual construction and need not be further described herein.

The suction head body 16 is supported upon the end of the tubular rod 13. This suction head construction is best shown in Figure 2. The body 16 has an axial passage 17 therethrough, this passage being internally threaded, as shown in the drawing. The intake end 18 of the body is provided with a thread adapted to take the end of the tubular rod passage 13, while the remainder of the body is provided with a uniform thread. The Venturi member 19 is threaded into the discharge end of the body 16 and may be retained in adjusted position by the lock nut 20. The enlarged end 21 of the member 19 is shown to be formed as a hex nut so as to facilitate the adjustment. Since in the use of these devices the plates which are handled thereby are often pushed by means of this end of the suction head, it is preferably hardened so as to stand up under considerable abuse.

The bore through the Venturi member 19 is provided with an intermediate reduced section section 22, enlarged end sections 23 and 24, and with gradually tapering sections 25 and 26 joining the end sections and intermediate section. The jet holder 27 is threaded into the bore 17 of the body 16 and holds the tubular jet member 28. The jet member 28 has the tubular passage 29 therethrough communicating with the tubular passage 30 through jet holder 27. As shown at 31, the outer wall of the jet member 28 is tapered adjacent the discharge end of the jet. The jet holder 27 is provided with notches 32 so that it may be adjusted in the body by means of a screwdriver. The tubular locking plug 33 is threaded into the body 16 and is jammed up against the jet holder 27 when that is in adjusted position, to serve as a lock nut and maintain it in such position.

The suction head body 16 of the form of construction shown in Figures 1 and 2 is provided with the lateral extension 34 having a suction bore 35 therein which intersects the axial bore 17 of the suction head body. The nipple 36 is threaded into the bore 35 and holds the plate 37 against the outer end of the lateral extension 34. The suction nipple 38 is threaded into nipple 36 and retains in place the plate 39, which plate serves to hold the rubber suction cup 40 against plate 37. It will be noted that the lateral suction bore 35 is shown as intersecting the axial bore 17 of the body at an intermediate point on the jet tube 28.

The form of construction shown in Figure 3 differs from that shown in Figures 1 and 2, in that the body 50, which is supported in the usual way upon the tubular rod 13, is provided with two lateral extensions 51 and 52, each of which supports a suction cup. These suction cups 53 and 54 are connected internally by passages with the central bore 50 in substantially the same manner as the connection of the single cup shown in Figure 2.

In the operation of the device the pipe or hose 12 is connected to a source of air or other fluid under pressure. When the trigger 15 is depressed to open the valve and permit passage of this fluid, it flows through the tubular rod 13, through the locking plug 33, the jet holder 27, the jet 28, and is discharged through the Venturi member 19. As it passes out of the jet and through the Venturi member it causes a substantial suction 20 through the suction nipple 36 and through the tubular opening 41 in the nipple 38. If the rubber suction cup 40 is placed upon a plate of metal or sheet of any material substantially impervious to air, sufficient suction is created so that very 25 substantial lifting force may be applied to lift the article through the suction attachment.

The actual amount of suction will depend upon the pressure of the discharge through the jet 28. The suction also may be varied within considerable limits by adjusting the relationship of the jet to the Venturi member and by adjusting both of them to the lateral suction opening in the suction head body. I have found, however, that it is usually not necessary to change the adjustment of the relationship between the jet and the lateral suction passage. Once the optimum location has been determined, further adjustment because of changes in fluid pressure may be taken care of under normal conditions by slight 40 adjustment of the Venturi member 19.

The structure shown is simple and composed of but few parts. It will be apparent that any of these parts may be removed and replaced without difficulty and without requiring special tools. 45 The device is used to move plates upon punch presses or the like, and often when the suction is released by releasing the trigger 15 and cutting off the fluid flow, the plate or other object being handled will not be up against the stops or in 50 exactly the proper position on the machine. It is therefore, as has been stated, customary for operators to use the end of the device, which in the present construction is the enlarged end 21 of the Venturi member, to push the work around, 55 so as to bring it up against the stops for the operation of the punch press, drill press or other machine in connection with which the device is used. It will be apparent that this member can be readily replaced when worn or broken by 60 such use or abuse. If the entire Venturi device is hardened the inner Venturi surface will also be less susceptible to wear by any foreign material blown through it with the compressed air.

It will be apparent that the size and relation-

ship of the parts may be varied as required. For example, the length of the tubular rod 13 may be changed depending upon the machine used or the size of parts handled and also the suction cups may be smaller or larger. I contemplate, therefore, such changes and modifications as come within the spirit and scope of the appended claims.

I claim:

1. A suction lifting device comprising a suction head body having an axial passage therethrough, a suction passage through a lateral wall of the body intersecting the axial passage, the axial passage being progressively reduced and expanded to one side of the passage intersection, 15 and a reduced discharge nozzle extending across the intersection centrally of the axial passage, said discharge passage terminating adjacent the progressively reduced portion of the axial passage. 20

2. A suction lifting device comprising a suction head body having an axial passage therethrough, a suction passage through a lateral wall of the body intersecting the axial passage, a tubular member threaded into the axial passage on one 25 side of said suction passage, said member having its opening progressively reduced and expanded at an intermediate portion thereof, a second tubular member threaded into the axial passage upon the opposite side of the suction passage, said 30 second member having a reduced tubular portion extending centrally of the axial passage across the intersection of the suction passage therewith, and terminating within the first member spaced from the inner wall thereof. 35

3. A suction lifting device comprising a suction head body having an axial passage therethrough, a suction passage through a lateral wall of the body intersecting the axial passage, a tubular member threaded into the axial passage on one 40 side of said suction passage, said member having its opening progressively reduced and expanded at an intermediate portion thereof, a second tubular member threaded into the axial passage upon the opposite side of the suction passage, said 45 second member having a reduced tubular portion extending centrally of the axial passage across the intersection of the suction passage therewith, and terminating within the first member spaced from the inner wall thereof at a point where the size of the opening through the first member has been somewhat reduced in size. 50

4. A suction lifting device comprising a suction head having an axial passage therethrough, 55 said head having a suction passage intersecting an intermediate portion of the axial passage, the axial passage on one side of the suction passage having substantially a Venturi form, and a reduced jet passage extending from the other portion of the axial passage across the junction of the axial and suction passages and discharging adjacent the reduced portion of the venturi. 60
